UNITED STATES PATENT OFFICE.

FREDERIC MERRIMAN, OF MILL VALLEY, CALIFORNIA.

DESIGN FOR AN ADVERTISING DEVICE.

59,253.

Specification for Design.

Patented Oct. 4, 1921.

Application filed January 10, 1921. Serial No. 436,375. Term of patent 7 years.

To all whom it may concern:

Be it known that I, FREDERIC MERRIMAN, a citizen of the United States, and a resident of Mill Valley, county of Marin, and State of California, have invented a new, original, and ornamental Design for an Advertising Device, of which the following is a specification, reference being had to the accompanying drawing, forming part thereof.

The figure is a perspective of the device.

The device consists of a housing for a coffee grinder or the like, the housing characterized in design by dominant features representative of a Dutch windmill.

What is claimed is:

The ornamental design for an advertising device, as shown and described.

FREDERIC MERRIMAN.
